RAILWAY JOURNAL LUBRICATOR

James J. Hennessy, Chambersburg, Pa., assignor
to Hennessy Lubricator Company, Inc., Cham-
bersburg, Pa., a corporation of Delaware

Application June 10, 1950, Serial No. 167,409

27 Claims. (CL 308—84)

1

The invention relates to lubricators for railway axle journals and comprises a device for pumping lubricant from a sump below the journal and distributing it to the face of the journal, the pump being operated by the play of the journal crosswise of the box mounted on the journal as is characteristic in railway rolling stock.

More particularly the invention preferably consists in a pumping and distributing assembly and a supporting and holding assembly, all adapted to be inserted as a unit through the usual opening in the outer end of a journal box of American Association of Railroads general construction to position the pumping and distributing assembly beneath the journal, the supporting and holding assembly being readily positioned and secured in place by parts yieldingly thrusting against spaced portions of the box and journal.

The principal objects of the invention are to construct a lubricator of the type described which is readily applied to and removed from a journal box and journal bearing assembly and may be accurately positioned irrespective of manufacturing variations in the length, width, or depth of the box without any preliminary adjustments and without requiring permanent additions to the box or any machining of the box for the purpose of applying the lubricator.

Other detail objects of the invention will be apparent from consideration of the present disclosure including the accompanying drawings, in which—

Figure 1 is a longitudinal vertical section through the journal of a railway axle and an A. A. R. journal box mounted thereon by means of the usual bearing and wedge.

Figure 2 is in part a vertical transverse section taken on the line 2—2 of Figure 1 and in part a front elevation of the end of the journal and the adjacent portion of the lubricator.

Figures 3 and 4 are detail vertical transverse sections taken on the corresponding section lines of Figure 1.

Figure 5 is a vertical longitudinal section through the forward portion of the journal and box shown in Figure 1 but showing the lubricator as it is being applied or removed from the box.

Figure 6 is a top view of the lubricator alone.

Figures 7 and 8 correspond to Figures 1 and 2, but illustrate another form of the invention.

Figure 9 is a perspective illustrating a journal, journal box, bearing, wedge, and lubricator assembly and showing a lubricator differing in some details from those shown in Figures 1—8.

In Figures 1—6, the railway axle journal 1, its

2

bearing 2, wedge 3 and box 4 are of usual construction. The lubricator includes a pump 5, a pump operating device 6, a lubricant distributor 7, supporting legs 8 and 9, and a positioning strut 5 including elements 10, 11, 12, and 13. Legs 8 and 9 are pivoted at their upper ends to distributor 7 and diverge downwardly and engage the transversely curved bottom wall 14 of the journal box (Figures 3, 4) which curves forwardly and upwardly at 16 (Figure 1) and is not there engaged by leg 9. Leg 8 also contacts the box rear wall 15. The strut 10, 11, 12, 13 is pivoted to the outer end of leg 9 and extends upwardly therefrom. Element 11 telescopingly receives element 12, which is thrust upwardly by springs 17. Terminals 18 at the upper end of element 12 are recessed to better engage the downwardly facing rib 19 on the journal box top wall 20 to anchor the lubricator in position. The downward thrust of springs 17 urges elements 11, 13, 10, 9, 7, and 8 downwardly and inwardly until the outer end of leg 8 engages a box rear wall 15, whereupon continued thrust urges the ends of legs 8 and 9 nearest each other, and distributor 7, upwardly so that the distributor contacts the journal.

Preferably the distributor comprises a part 22 of fibrous material such as felt, rope, or woven yarn, sewed or otherwise attached to a backing sheet 23 of waterproof fabrics, such as canvas. This part is carried on three flexible sheet metal strips 24, 25, and 26, each extending from side to side of part 22 and spaced from the adjacent strip or strips longitudinally of the distributor. Bars 27, 28, and 29 are arranged end to end near each side of the distributor and they are pivoted to each other as indicated at 30 to cooperate with flexible strips 24, 25, 26 to permit distortion of the distributor, as best shown in Figure 5, to accommodate its passage into and out of functioning position. Supports 8 and 9 are pivoted to bars 27 and 29 at 31 and 32, respectively.

Pivoted on cross bar 33 of support 9 is an inwardly extending carrier 34 and positioned between the inner end of this carrier and distributor 22 is pump 5, comprising one or more collapsible chambers with return check valve inlets 35 and outlets 36, there being springs 37, 38, 39 urging the pump chambers to expanded position. Pivoted on cross bar 40 of support 9 is a lever having an upstanding arm 41, with a terminal disposed to engage the outer face of the journal. The lever has a relatively short arm 42, the outer end of which contacts the underside of carrier 34.

When journal 1 moves to the left from the position shown, lever 41, 42 is rotated in an anti-

clockwise direction, lifting carrier 34 and collapsing pump 5 to force fluid in the pump through valves 36 and to the distributor. When journal 1 moves in the opposite direction, springs 37, 38, 39 move the pump parts, carrier 34 and lever 41, 5 42 to the position shown, or to a more extreme position, closing valves 36 and drawing fluid into the pump through valves 35. Continued operation of the lubricator in this manner maintains a supply of lubricant from the bottom of the box to the journal. The construction and operation of the pump itself are disclosed and claimed in more detail in applications filed December 7, 1949, now Patent No. 2,639,200, issued May 19, 1953, and February 15, 1950, Serial No. 144,288, abandoned in view of a continuation application filed 10 August 14, 1952, Serial No. 304,277.

Preferably the lubricator includes structure for closing off the space between the lower half of the journal and the edge of the opening thereto in wall 15 which forms the inner wall of the usual oil and dust guard pocket 43. This structure is mounted upon support 8 and comprises two arcuate strips of felt-like packing material 44, 45, respectively, strip 44 being pressed against box rear wall 15 and a similar strip 45 being pressed against the arcuate fillet between the axle body and the inner end of journal 1. Strip 44 is mounted on a backing plate 46 which is supported by spring pressed plungers 47 slideable in uprights 48 pivoted at 49 to arms 50 on support 8. Elements 44, 45 are thrust in a clockwise direction by a spring 51 anchored to support 8 with its intermediate portion looped and slidably received in clips 52 on plate 46. A sheet of leather-like material 53 extends upwardly from the upper edge of plate 46 and mounts strip 45. A spring device 54, similar to spring 51, is carried by plate 46 and thrusts the upper portion of sheet 53 and strip 45 against the journal fillet. 20

This sealing structure accommodates the movement of the journal back and forth in the box and provides for the contact of the felt strips with the box rear wall and journal fillet, irrespective of variations in the length of the box or the distance between the bottom of the journal and the box bottom wall. The sealing structure is automatically positioned by the insertion of the remainder of the lubricator into the box, and without requiring the operator to thrust his hands or a tool to the inner end of the box to adjust the seal.

In Figures 7 and 8 the journal, bearing, wedge, box, distributor, and pump are substantially the same as the corresponding parts described above. The supporting and holding assembly differs from that previously described in several respects. Supports 61 and 62 have their upper ends pivotally connected to each other and to the central section 63 of the distributor by a single pin 64. Support 61 is substantially the same as support 8, but somewhat longer and is not shown with the seal for the space between the journal and the edge of the oil and dust guard pocket, although such sealing structure as shown in Figures 1 and 4 could be mounted upon support 61 if desired.

Support 62 corresponds to support 9 but is substantially longer and its outer end is pivoted at 65 directly to the telescoping unit comprising an H frame with legs 66 and a cross bar 67. Legs 66 are tubular at 68 to receive plungers 69 surrounded by springs 70 and carrying terminal anchors 71.

Preferably rollers 72 are journaled on leg 62 and are positioned to engage the box wall 14a—

16a, and facilitate the inward movement of the structure to the assembled position shown in Figure 7. The square angle between the periphery and the outer face of each roller causes the roller to resist rotation of the distributor as a whole about the journal axis as might be induced by the friction between the journal and the distributor when the axle is beginning to rotate and the journal has not been lubricated, particularly in cold weather.

The pump operating device comprises a single rigid lever pivoted intermediate its ends on a cross member 78 of support 62 and having an upwardly extending arm 79 with a terminal 74 for engagement with the end of the journal and having an inwardly extending horizontal arm 75 supporting the lower portion of the collapsible pump 76 which corresponds generally to the pump shown in Figures 1 and 2.

Support 62 functions as a lever fulcruming at its rollers 72 on the adjacent surface of the journal box with its outer end thrust downwardly by spring 70 and its inner end thrust upwardly against the distributor 77. With this construction the distributor 77 is applied to the journal by thrust exerted along a central transverse line and readily pivots on pin 64 to contact the journal throughout the length of the distributor.

This construction has fewer parts and is simpler than that shown in Figures 1-6 but embodies most of the essential elements of the lubricator.

Figure 9 illustrates a structure corresponding generally to that shown in the above-described figures but differing in the following respects.

The right hand supporting and position unit comprises a central member 80 extending downwardly and inwardly from the distributor and terminating in an arcuate cross member 81 seated in the corner formed by the box bottom wall 14b and rear wall 15b. The left hand supporting and positioning unit comprises pairs of two interconnected parts 82, 83 hinged together by pins 84 in brackets 85, each having a depending lug 86 engaging the box bottom wall and preferably formed of hardened steel so that its edges will dig into the box wall and more effectively resist rotation of the lubricator with the journal. A telescoping yielding strut 87 with anchors 88, corresponding to those previously described, is pivotally connected to the outer ends of parts 83 and thrusts the latter downwardly from its seats on the box top wall 20b and against the box wall 14b—16b. The telescoping yielding strut and the pivoted elements 83, 82, 80 thrust the distributor rearwardly and upwardly and position the distributor and pump lengthwise of the box, irrespective of substantial variation in box lengths as is found in such boxes which are made by different manufacturers and to varying degrees of accuracy.

The carrier 89 of the pump operating mechanism is pivoted at 90 to brackets 85 and includes a tail piece 91 terminating in a cup 92 which seats springs 93, the upper ends of which bear against the lower face of the plate-like operating lever 94 which is provided with transversely spaced contacts 95 at its upper end for engaging the end of the journal.

The flexible wall pump body 96 is normally extended by a single interior spring. This pump comprises a single chamber with one or more inlet valves at its lower hand end and outlet valves at its upper end leading to the distributor.

The distributor comprises a single bottom plate

97 and a sheet 98 of woven fibrous material for application to the journal. Plate 97 possesses sufficient flexibility to be curved as required to pass between the end of the journal and the edge of the opening in the box end wall during insertion and removal of the lubricator into and from operating position.

A torsion spring 102, coils about the pivot 103 through which the supports are connected to the distributor and has its ends seated against the distributor and the right hand support and positioning arm 80 and thrusts arm 80 downwardly to insure its contacting with the bottom of the box when the lubricator is installed.

A guard 104 is pivoted to the right hand end 15 of carrier 89 and is looped around arm 80 and serves as a guard to avoid the lower edge E of the journal box opening from being received between arms 80 and 89 and catching the side 20 of the pump body and injuring the same, or otherwise interfering with the installation of the lubricator.

Eccentric buttons 105, threaded onto carrier 89, when in one angular position, overlie the laterally projecting bottom plate of the pump and hold it to the carrier. When pins 105 are rotated 180°, the pump may be released from the carrier 89. If, at the same time, pivot pin 103 is withdrawn, the distributor and pump unit 25 may be removed from the remainder of the lubricator structure. This is an advantageous feature, permitting the ready replacement of worn pump and distributor parts.

It will be understood that the seal shown in Figures 1 and 4 may be mounted on the cross 35 member 81, if this feature is desired.

Each form of the invention comprises a single unit including the distributor, pump, supports and, if desired, the seal for the opening in the box rear wall, all readily inserted, through the usual opening in the front of the box, into functioning position and just as readily removed by detaching anchors 18, 71, or 88 from the position 40 of the box they engage and swinging the adjacent framing outwardly of the box and then swinging the remaining portions upon their interconnected pivots, compressing the pump and flexing the distributor as required to move these parts outwardly between the journal collar and the upwardly and forwardly curved end wall of the box. Obviously features of the invention may be embodied in less than the more complete groups illustrated. A substantially smaller distributor and a different type of pump could be used in place of those shown, or one of these elements could be omitted, without departing from the general principle of the invention involving the positioning of a lubricator device in the box by means of a series of pivoted members held in functioning position by the yielding thrust against oppositely facing surfaces of the box assembly.

The details of construction may be varied otherwise and the exclusive use of those modifications of the invention coming within the scope of the claims is contemplated.

What is claimed is:

1. In combination with a railway axle journal and a box mounted thereon, a mechanism for supplying lubricant from the bottom of the box to the journal, a linkage supporting said mechanism from the bottom of the box, and a yielding thrust member connected to said linkage and engaging a downwardly facing element on the box 75

to hold said linkage and mechanism in proper functioning relation to the journal.

2. In a railway axle journal lubricator, a distributor arranged for application to a journal, a plurality of supports, each having an inner portion pivotally connected to said distributor, one of said supports being inclined downwardly and towards one end of the distributor, the other support being inclined downwardly and towards the other end of the distributor, and a telescoping positioning strut pivotally connected to the outer portion of one of said supports and including spring structure yieldingly elongating said strut.

3. In a railway axle journal lubricator, a lubricant distributor with an upwardly concave surface curved transversely of the length of the distributor, a lubricant pump depending from the distributor, and a support for the distributor and pump comprising a pivot element on the distributor extending transversely of the length of the distributor intermediate its ends, and legs connected to said pivot element and diverging downwardly therefrom, there being yielding means for thrusting the diverging ends of said legs towards each other.

4. In a railway axle journal lubricator, an elongated arcuate distributor shaped to fit against the underside of a journal, structure for supporting said distributor comprising pivot elements on the distributor and extending transversely of the length of said distributor and spaced apart lengthwise of the distributor, a leg connected to each of said pivot elements, said legs diverging downwardly, and an elongated longitudinally yielding device associated with at least one of said legs and extending upwardly beyond one end of and above the level of said distributor and adapted to oppose a downwardly facing support journal box part for thrusting the diverging portions of said legs towards each other.

5. In a railway axle journal lubricator, an elongated distributor adapted for application to the underside of a journal, a support for said distributor comprising a pivot element on the distributor extending transversely of the length of the distributor intermediate its ends and legs connected to said pivot and diverging downwardly therefrom, and a strut pivotally connected to one of said legs and comprising telescoping members with spring structure thrusting its members apart, the outer end of said strut terminating in an anchor for engaging a journal box part spaced above the distributor.

6. In a railway axle journal lubricator, an elongated distributor adapted for application to the underside of a journal and comprising a plurality of sections hinged together to swing transversely of the journal engaging surface of the distributor, a support for the distributor comprising legs, each pivotally connected to an individual one of said sections, said legs diverging downwardly and a yielding strut pivotally connected to one of said legs and comprising telescoping members, and spring structure thrusting said members apart.

7. In a railway axle journal lubricator, an elongated distributor adapted for application to the underside of a journal and comprising a plurality of sections hinged together to swing transversely of the journal engaging surface of the distributor, a support for the distributor comprising legs pivoted to one of said sections, said legs diverging downwardly lengthwise of the distributor, and a yielding strut pivotally connected to one of said

legs and comprising telescoping members, and spring structure thrusting said members apart.

8. In combination with a railway axle journal and a journal box mounted thereon, a lubricant distributor applied to the journal, a plurality of members each having a portion pivotally connected to said distributor and having a portion spaced from the distributor and engaging an upwardly facing surface of the journal box bottom wall, to support the distributor, and engaging a laterally facing surface of a journal box upright wall to position the distributor lengthwise of the box.

9. In combination with a railway axle journal and a journal box mounted thereon, a lubricant distributor applied to the lower portion of the journal, supports for said distributor, at least one of which supports has a fulcrum intermediate its ends which engages the bottom wall of the journal box, and a yielding strut-like device secured to the outer end of one of said supports and engaging a downwardly facing element on the box.

10. In combination with a railway axle journal and a journal box mounted thereon, a distributor applied to the journal, a pair of members pivotally connected to the distributor and with their outer ends spaced apart and engaging the bottom wall of the box and contacting the front and rear walls of the box, respectively, and yielding means connected to the outer end of one of said supports and abutting the top wall of the box.

11. In combination with a railway axle journal and a journal box mounted thereon, a lubricant distributor applied to the journal, a plurality of members the upper portions of which are spaced apart longitudinally of the journal and are pivotally connected to said distributor and the lower portions of which members engage the lower wall of the box to support the distributor, and yielding strut-like means between at least one of said members and a downwardly facing element on the box and thrusting the lower portions of said members towards each other and thereby thrusting said distributor against the journal.

12. In combination with a railway axle journal and a journal box mounted thereon, a lubricant distributor applied to the underside of the journal, a lubricant pump carried by the distributor, a pair of elongated supports arranged end to end, there being a common pivotal connection between their adjacent ends and said distributor, said supports having portions remote from said pivotal connection engaging spaced portions of the lower wall of the box, and means yieldingly thrusting said portions towards each other and thrusting said pivotal connection and distributor upwardly.

13. In a railway axle journal lubricator, a lubricant distributor for application to the lower portion of the journal, a pair of elongated supports, there being a pivotal connection between one end of each support and said distributor, a pump suspended from the distributor, and a pump operating device movably carried on one of said supports independently of the pump and having a part disposed to engage the end of a journal to which the distributor is applied.

14. In a railway axle journal lubricator, a distributor for application to a journal, a support for said distributor extending downwardly therefrom, a carrier pivoted to said support and extending under said distributor, a collapsible pump

5 between said carrier and distributor, and a pump operating lever pivoted on said support and having an arm associated with said carrier and an arm disposed to be engaged by the end portion of a journal to which the lubricator is applied.

15. In combination with a railway axle journal and a journal box mounted thereon, a lubricant distributor applied to the lower portion of the journal, a member extending from said distributor towards the bottom and rear walls of the box, a member extending from said distributor towards the bottom and front walls of the box, said members supporting the distributor and holding it against movement lengthwise of the box by its engagement with said walls, a pump associated with the distributor, a pump operating lever mounted on said latter-mentioned member and including an arm engaging the end portion of the journal, there being a yielding strut member extending from said pump mounting member upwardly with its upper end seated against a portion of the box above the level of said distributor.

16. In combination with a railway axle journal and a journal box mounted thereon, a distributor applied to the lower portion of the journal, a pump suspended from said distributor and comprising collapsible chambers, a pump operating device associated with said pump, and means mounting said device in the box independently of the pump, said means including a part supported by the bottom of the box and positioned lengthwise of the box by contact with the box rear and front walls.

25 17. In a railway axle journal lubricator, a distributor arranged for application to a journal, a support member pivoted to said distributor, and a sealing device movably mounted upon said support member and comprising elongated strips of 30 packing material extending generally in a direction transversely of the distributor, and including yielding means thrusting said material lengthwise of the distributor and away from the adjacent end thereof.

40 18. In a railway axle journal lubricator, a distributor arranged for application to a journal, a support member pivoted to said distributor, and a sealing device comprising relatively movable strips of packing material, extending generally in a direction transversely of the distributor, and a mounting for said strips carried on a portion of said support member spaced from its connection to the distributor.

45 19. In a railway axle journal lubricator, a distributor arranged for application to a journal, a support member pivoted to said distributor, a sealing strip of compressible material extending in a general direction transversely of the lubricator, a mounting therefor carried on said support member at a point spaced from the connection of the latter to the distributor, and spring means thrusting said mounting and strip away from the distributor.

55 20. In combination with a railway axle and journal having an arcuate fillet between them, and a journal box mounted thereon, said box having a rear wall provided with an opening substantially larger in diameter than said journal and axle, a lubricator including a distributor applied to the lower portion of the journal, a flexible packing for sealing the space between the journal and the edge of said opening, said packing being movably mounted upon the lubricator, means thrusting said material against said box wall, and

other flexible packing movable relative to said first-mentioned packing and means thrusting the second-mentioned packing against said fillet.

21. In a railway axle journal lubricator, a distributor arranged for application to a journal, a plurality of elongated supports for said distributor diverging downwardly away from the distributor, a pump positioned at least in part in the space between said supports and a guard extending between said supports near the level of the bottom of said pump to protect the pump from contact with external objects tending to move between said pump and towards said distributor during installation to a journal.

22. In a railway axle journal lubricator, a distributor arranged for application to a journal, a plurality of supports, each having an inner portion pivotally connected to said distributor, one of said supports comprising legs spaced transversely of the distributor and inclined downwardly and towards one end of the distributor, a pump positioned between said legs, the other support comprising a single leg inclined downwardly beneath the longitudinal center line of the distributor and towards the other end of the distributor.

23. In a railway axle journal lubricator, a distributor arranged for application to a journal, members for supporting said distributor pivoted thereto and extending downwardly therefrom, a yielding thrust member extending upwardly from one of said supports and adapted to engage a downwardly facing element of a box to which the lubricator is applied, there being a roller journaled on said support to facilitate movement of the support over the journal box wall longitudinally of the distributor, said roller having sharp corners transversely of the distributor to resist rotation of the lubricator with the journal to which it is applied.

24. In a railway axle journal lubricator, a distributor arranged for application to a journal, a plurality of supports, each having an inner portion pivotally connected to said distributor, a pump associated with the distributor, a pump operating mechanism associated with one of the supports and disposed to be engaged by a journal to which the distributor is applied, one of said supports being inclined downwardly and towards one end of the distributor, the other support being inclined downwardly and towards the other end of the distributor, and a telescoping positioning strut pivotally connected to the outer portion of one of said supports and including spring structure yieldingly elongating said strut.

25. In a railway axle journal lubricator, an

elongated distributor adapted for application to the underside of a journal and comprising a plurality of sections hinged together to swing transversely of the journal engaging surface of the distributor, a support for the distributor comprising legs pivoted to one of said sections, said legs diverging downwardly lengthwise of the distributor, a yielding strut pivotally connected to one of said legs and comprising telescoping members, spring structure thrusting said members apart, a pump associated with the distributor, and a pump operating lever pivoted on the leg to which the yielding strut is connected, said lever having an arm connected to said pump and having an arm disposed to be engaged by the journal to which the distributor is applied.

26. In a railway axle journal lubricator, a distributor arranged for application to a journal, a support member pivoted to said distributor, a sealing strip of compressible material extending in a general direction transversely of the lubricator, a mounting therefor pivoted on said support member at a point spaced from the connection of the latter to the distributor and spring means thrusting said mounting and strip away from the distributor, a second sealing strip of compressible material carried on said mounting, and separate spring means thrusting said second strip away from said distributor.

27. In combination with a railway axle journal and a journal box mounted thereon, a lubricant distributor applied to the lower portion of the journal, support structure for said distributor including an elongated part extending lengthwise of the distributor and having a fulcrum intermediate its ends engaging the bottom wall of the journal box, a spacing member connected to one end of said part and engaging the rear wall of the box, there being a yielding strut-like device secured to the other end of said part and engaging a downwardly facing element on the top wall of the box.
